CLAIM

The ornamental design for a portable leather keyboard as shown and described.

DESCRIPTION

FIG. 1 is a perspective view of a portable leather keyboard in a use status showing the claimed design; FIG. 2 is another perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is a perspective view of a portable leather keyboard in a portable status; FIG. 10 is a perspective view of the portable leather keyboard of FIGS. 1-8, shown in a closed configuration with the handle folded into the body. FIG. 11 is an enlarged view of area 11 shown in FIG. 1; FIG. 12 is an enlarged view of area 12 shown in FIG. 1; FIG. 13 is an enlarged view of area 13 shown in FIG. 1; FIG. 14 is an enlarged view of area 14 shown in FIG. 1; FIG. 15 is an enlarged view of area 15 shown in FIG. 1; FIG. 16 is an enlarged view of area 16 shown in FIG. 3; FIG. 17 is an enlarged view of area 17 shown in FIG. 5; and, FIG. 18 is an enlarged view of area 18 shown in FIG. 5. The evenly-spaced broken lines show portions of the portable leather keyboard that form no part of the claimed design; the dash-dot-dash broken lines represent enlarged sectional designations that form no part of the claim.

1 Claim, 18 Drawing Sheets
